(57) **CLAIM**

The ornamental design for a handbag, as shown and described.

DESCRIPTION

FIG. 1 is a front perspective view of a handbag showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of a handle, rear of bag, bottom strap, rivets, and wrap around piece is included for the purpose of showing environmental portions of the handbag and form no part of the claimed design.

The four rows of evenly spaced dashed lines shown on the top flap of the handbag in FIGS. 1, 2, and 7 represent conventional stitching.
